UNITED STATES PATENT OFFICE.

HENRY B. BURIN, OF NEW YORK, N. Y.

MACHINE FOR THREADING BOLTS AND NUTS.

SPECIFICATION forming part of Letters Patent No. 237,479, dated February 8, 1881.

Application filed April 7, 1880. (No model.)

To all whom it may concern:

Be it known that I, HENRY B. BURIN, of the city, county, and State of New York, have invented a new and useful Improvement in 5 Machines for Threading Bolts and Nuts, of which the following is a specification.

Figure 1, Sheet 1, is a plan view of the improvement. Fig. 2, Sheet 1, is a sectional elevation taken through the line $x-x$, Fig. 1. 10 Fig. 3, Sheet 2, is a sectional elevation taken through the line $y-y$, Fig. 1. Figs. 4, 5, and 6, Sheet 2, are detail views of one of the work-holders. Fig. 7 is a sectional elevation showing the tongues and grooves by which wheels and shafts are connected. Fig. 8 is a plan view of the segmental gear-wheel, the wheels 15 that gear with it, and the diagonal shafts.

Similar letters of reference indicate corresponding parts.

20 The especial object of this invention is to furnish machines for cutting bolt-threads and tapping nuts, so constructed that as one die or tap is forced forward to do its work another die or tap will be withdrawn from its work, so that the machine will work continuously and 25 no time will be lost in withdrawing the die or tap.

The invention consists in the combination, 30 with the sliding rotary shafts that carry the tools, of the ring gear teeth and the equal-armed lever, having curved cross-head racks upon its ends, whereby the one shaft is moved longitudinally in one direction by the longitudinal movement of the other shaft in the 35 other direction; and also in constructing the work-holders of a stationary plate having notches for the cleaning-brush to pass through and to discharge the work, the stationary upper plate having notches for the cleaning-brush to pass through and to admit the work, 40 and the intermediate revolving plate or head attached to a spindle and having notches to receive the work and chips, whereby the work will be received, held while being operated upon, and discharged, and the chips can be 45 removed, as will be hereinafter fully described.

A represents the frame of the machine. B B' are two parallel shafts, which I prefer to make hollow to allow them to have a suitable size and strength without being too heavy.

The shafts B B' revolve and slide longitudinally in bearings attached to the frame A.

To the ends of the shafts B B' are attached holders C, to receive a tap, D, for tapping nuts, or holders E, to receive dies F, for cutting screw- 55 threads upon bolts. If desired, tap-holders C may be attached to both ends of both shafts, or die-holders E may be attached to both ends of both shafts; or one or both shafts may have a tap-holder, C, at one end, and a die-holder, 60 E, at the other end, as circumstances may require.

Upon the shafts B B' are placed two large gear-wheels, G G', the teeth of which mesh into each other, so that the shafts B B' may 65 be revolved at the same time and in opposite directions. The gear-wheels G G' are swiveled to the bearings of the shafts B B', and are connected with the said shafts by tongues and grooves, so as to carry the shafts B B' with them 70 in their revolution, while allowing the said shafts to have a free longitudinal movement.

Into the teeth of one of the gear-wheels G G' mesh the teeth of a small gear-wheel, H, attached to a short shaft, I, which revolves in 75 an arm or bracket formed upon or attached to the frame A, and has a small bevel-gear wheel, J, attached to its outer end. The teeth of the bevel-gear wheel J mesh into the teeth of a small bevel-gear wheel, K, attached to the shaft 80 L, which revolves in bearings attached to the frame A, and has a fast pulley, M, and a loose pulley, N, attached to its end to receive the driving-belt.

85 O are sockets or bearings formed in or attached to the frame A, and in which revolve vertical spindles P, having circular heads Q attached to their upper ends. The heads Q are made of a thickness equal to the width of the nut or the head of the bolt to be operated upon. 90

In the edges of the heads Q, and at equal distances apart, are formed five radial notches, R, of such a size as to receive the nuts or the heads of the bolts to be operated upon, and of a depth equal to the thickness of the 95 said nuts or bolt-heads. In the heads Q, at the bottoms of the notches R, are formed narrower radial notches S, to receive the chips made by the tapping-tools in cutting the threads. Each head Q is placed between two 100

circular plates, T U, the lower one, T, of which is formed upon or attached to the upper end of the socket O. The upper plate, U, is secured in place by bars V, attached to its edge and 5 to the edge of the lower plate, T. In the plates T U, directly over each other, are formed notches W X, corresponding with the notches R S of the heads Q, so that as the said notches R S come successively into place between the 10 notches W X of the plates T U, a brush, Y, may be passed through the said notches to remove any chips that may be in the notches, and thus clean them ready to receive another nut or bolt-head. The brush Y may be operated 15 to pass it through the notches in the plates T U and head Q by a lever and cam or other suitable mechanism, which mechanism is not shown in the drawings. In the upper plate, U, in front of the notch W, and 20 at a distance from it equal to the distance between the notches R in the head Q, is formed a notch, Z, equal in size to the notches R W, through which the nut or bolt-head is passed in inserting it in the notches R of the head Q. 25 As the head Q moves forward, the nut or bolt-head is kept in place in the notch R by the solid parts of the plates T U, between which it is carried.

In the lower plate, T, in the rear of the 30 notch W, and at a distance from it equal to the distance apart of the notches R in the head Q, is formed a notch, a, of the same size as, or a little larger than, the notches R W Z, to allow the nut or bolt-head to drop through 35 when it is brought over the said notch a by the head Q.

To the lower ends of the spindles P are attached small bevel-gear wheels b, into the teeth of which mesh the teeth of the bevel- 40 gear wheels c, attached to the ends of the two shafts d. The two shafts d revolve in bearings attached to the frame A, and pass through the said frame A diagonally, so that the diagonal heads Q may be moved together.

To the middle parts of the shafts d are attached small bevel-gear wheels e, the teeth of which mesh into the teeth of bevel-gear wheels f, attached to or formed upon the upper and lower sides of a gear-wheel, g. The bevel-gear wheels 45 f are segmental, the toothed segments being arranged to revolve the shafts d alternately, and at the proper intervals to turn the heads Q for the proper distance when the tools have been withdrawn from the nuts or bolts. The gear-wheels f g f are attached to a short vertical shaft, which revolves in bearings attached to the frame A, or to a bracket or hanger formed upon or attached to the said frame. The teeth 55 of the gear-wheel g mesh into the teeth of a small gear-wheel, h, attached to the shaft i, which revolves in bearings in the frame A, and to which motion is given from the driving-shaft through a suitable connecting gearing,

which connecting gearing is not shown in the drawings.

65

j represents a milling-tool, which revolves in some suitable support directly opposite the notch R, in the rear of the notch R, in which the die or tap works.

To the milling-tool j, or its holder, is attached a small bevel-gear wheel, k, into the teeth of which mesh the teeth of the bevel-gear wheels l, attached to the shafts m. The shafts m revolve in suitable supports, and are connected with and driven from the driving 75 mechanism of the machine by suitable connecting gearing, which connecting gearing is not shown in the drawings. The milling-tool j is intended to smooth off or round the end of a bolt, or to dress the face of a nut 80 and ream out the hole punched or drilled in the nut.

70

Upon the shafts B B' are formed series of ring gear teeth n, into which mesh the teeth of curved cross-head racks o, formed upon the 85 ends of an equal-armed lever, p, pivoted to the frame A. With this construction one of the shafts B B' will be moved longitudinally in one direction by the movement of the other shaft in the other direction, and both shafts 90 will be made to move at the same rate of speed. This construction is especially convenient when only one side of the machine is used, or when the shafts B B' have tool-holders at 95 only one end, so that the tool attached to the one shaft may be withdrawn by the advance of the tool attached to the other shaft.

90

Having thus described my invention, I claim as new and desire to secure by Letters Patent—

1. In a machine for cutting bolt-threads and tapping nuts, the combination, with the sliding rotary shafts B B', that carry the tools, of the ring gear teeth n and the equal-armed lever p, having curved cross-head racks o upon its ends, substantially as herein shown and described, whereby the one shaft is moved longitudinally in one direction by the longitudinal movement of the other shaft in the other direction, as set forth.

100

2. In a machine for cutting bolt-threads and tapping nuts, the work-holders constructed substantially as herein shown and described, consisting of the stationary lower plate, T, having notches W X a, the stationary upper plate, U, having notches W X Z, and the intermediate revolving plate or head, Q, attached to the spindle P, and having notches R S, whereby the work is received, held while being operated upon, and discharged, and the chips 115 can be removed, as set forth.
